(57) **CLAIM**

The ornamental design for a folding stand fan, as shown and described.

DESCRIPTION

FIG. 1 is a front, top, right perspective view of a folding stand fan showing my design therefor;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof; and,

FIG. 7 is a opposite side elevational view thereof.

Throughout the design, the broken lines are environment and form no part of the design.
